* INDEXING AND CHUCKING DEVICE

Byron F. Bower, Aurora, Ill., assignor to Pines
Engineering Company, Aurora, Ill., a corpora-
tion of Illinois

Application May 28, 1945, Serial No. 596,247

12 Claims. (Cl. 82—2)

1

The present invention relates to indexing and chucking devices for machines that operate upon one or both ends of a length of stock such as a tube or a rod. It is the principal purpose of the invention to provide means to feed and position the work at a high rate of speed so that the operating tools can be used to the maximum capacity with a minimum delay in the positioning of new work and the discharging of finished work.

It is also the purpose of my invention to provide in combination a reel feeding mechanism and an automatic self centering chuck so arranged that the lengths of tubing and the like can be advanced to chucking position along a proper center line and then seized by the chuck with a high degree of accuracy and speed. It is also the purpose of the invention to provide a novel mechanism for opening and closing the chuck itself in such a fashion that the work is rigidly held when the chuck is closed but the chuck is opened wide so that the reel can move the work into the chuck regardless of great variation in the size of the work.

The nature and advantages of my invention will appear more fully from the following description and the accompanying drawings wherein a preferred form of the invention is shown. It is to be understood however, that the drawings and descriptions are illustrative only and that they should not be considered as limiting the invention except insofar as it is limited by the claims.

In the drawings:

Figure 1 is a view in side elevation of a tube end finishing machine embodying my invention;

Figure 2 is a cross sectional view taken on the line 2—2 of Figure 1;

Figure 3 is a detailed view on a smaller scale of an adjustable support plate and its mounting means;

Figure 4 is a cross sectional view on the line 4—4 of Figure 3 illustrating the mechanism by which the adjustable support plate is moved;

Figure 5 is a cross sectional view through the chuck operating mechanism showing a modified form of the invention and;

Figure 6 is a side view partly in section taken at right angles to Figure 5.

Referring now in detail to the drawings, the present invention is embodied in a tube finishing mechanism although it will be obvious from the description that the invention is not limited to such machines. The invention is applicable to various types of machines for cutting and finish-

2

ing lengths of stock such as tubing, rods and the like. The present invention provides means whereby the stock can be fed from a supply source (not shown) and held in a proper position for the cutting or finishing operation to be performed thereon by tools located at one or both ends of the work holding device. As shown in the drawings a base 10 carries two spaced apart machines 11 and 12. The base 10 has a track 13 on which the machines 11 and 12 may be moved toward and away from each other to accommodate work of different lengths. Normally one of the machines 12 will be placed at one end of the base and the other machine will be adjustable with respect to the machine 12 along the track 13. I have shown the machines 11 and 12 as having cutting or finishing tool heads 14 and 15 thereon for performing work upon a work piece 16. The heads 14 and 15 are of course movable toward and away from the work.

The feeding mechanism by which the work is fed to position between the heads 14 and 15 comprises a shaft 17 which is journaled in two bearings 18 and 19 carried by the frames of the machines 11 and 12. These bearings are mounted upon plates 20 and 21 of the aforesaid frames. Two notched discs 22 and 23 are provided with hubs 25 and 26 that are fastened upon shaft 17. A ratchet wheel 27 is also secured upon the shaft 17 so that it may be utilized to rotate the shaft and the discs 22 and 23. In order to rotate the ratchet wheel 27 I provide a link mechanism 28 comprising two bars 29 and 30 connected together by a pin 31 that is adapted to ride over the teeth 27a of the ratchet wheel 27 and turn the ratchet wheel step by step. The link 28 is pivoted at 32 to a piston rod 33. The piston rod 33 is secured to a piston 34 and a hydraulic cylinder 35 to which hydraulic fluid is supplied first to one end and then to the other end from a suitable source. The piston 34 is thus reciprocated at definite intervals to advance the discs 22 and 23 in the direction of the arrow shown in Figure 2 in order to bring the work pieces 16 into position between the heads 14 and 15.

The work pieces such as 16 may be supported along side the discs 22 and 23 by a platform 36 which is indicated on Figure 2 of the drawings. These platforms are usually inclined so that the work may roll down against the discs and fill the notches as the discs are turned. The edges of the discs will of course, keep the work pieces in place until one of the notches is aligned with the foremost work piece. Between the machines 11 and 12 there is a frame work 37 that fits over the

bed 10 and engages the track 13. This frame is clamped in position by two wedge shaped bars 38 and 39 which extend between front and back portions 40 and 41 of the frame and the adjacent beveled faces of the track 13. The bars 38 and 39 are held in place by screw bolts 42 and 43.

The frame 37 has two adjustable support plates 44 and 45 at the opposite ends thereof. These support plates are movable up and down and on the frame 37 by means of studs that are fastened in the frame 37 and slots in the plates. In Figures 3 and 4, the adjusting means for the plates 44 and 45 are shown. Each plate is mounted on two studs 46 and 47 that are carried by the frame 37. Each plate has three vertically running slots 48 through which the studs and a lug 49 extend. The frame also has a lifting roller 50 pivoted thereon by means of a pivot pin 51. This roller has a handle 52 thereon by which it may be rotated on its pivot so as to raise and lower the plate 44 or 45 with respect to a cross bar 54 of the frame 37. It is essential that the plates 44 and 45 be readily adjustable since the work pieces ride on these plates as they are brought into position between the heads 14 and 15.

The plates 44 and 45 can be adjusted to satisfactorily align the work pieces with the heads 14 and 15 but in order for the work pieces to be acted upon by the cutting or finishing tools it must be held rigidly in place and this is accomplished by opposed pairs of chuck jaws 55 and 56. These jaws are adjacent to each of the end discs 22 and 23. In the case of extremely long work pieces it may be desirable to have several intermediate discs like 22 and 23 between the end discs 22 and 23. However, only two sets of chuck jaws are needed. These chuck jaws are pivoted upon a shaft 57 that is carried in the frame 37. Each of the jaws has a movable liner 58. The liners 58 are made up in different sizes to accommodate variations in size of the work pieces to be held. The chuck jaws 55 and 56 are provided with plane faces 59 and 60 which faces are tapered with respect to a vertical plane through the chuck jaws when closed and this taper is very slight. Wear plates 60 and 61 are provided on the tapered faces 59 and 60 for engagement with chuck closing rollers 62 and 63. The chuck closing rollers 62 and 63 move between the dotted and the full line positions shown in Figure 2 to close the chuck jaws 55 and 56 on a work piece 16. It will be noted that the chuck jaws, when they are in opened (dotted line) position, are below the top edges of the supporting plates 44 and 45 so that they do not interfere with the movement of a work piece when the shaft 17 is rotated to bring the work into position.

The means for operating the rollers 62 and 63 is best shown in Figure 2. The roller 62 is carried on a bell crank 64 which in turn is pivoted on a shaft 65 mounted on the framework 37. The lower arm of the bell crank 64 is bifurcated to receive one end of a link 66 which is secured by a pin 67 that extends through one side of the bifurcated end of the bell crank and is threaded into the opposite side. The other end of the link 66 is secured to the upstanding arm of a bell crank 69 which is pivoted on a shaft 70. The shaft 70 is secured in the frame 37. The other arm 71 of the bell crank 69 is pivoted by a pin 72 to an adjustable link 73. One end of the link 73 is pivoted by a pin 74 to a piston rod 75. The other end of the link 73 is pivoted by a pin 76 to the bifurcated end 77 of a bell crank 78. The bell crank 78 is pivoted on a shaft 79 and carries the roller 63.

A coupling 80 is provided between the ends of the link 73 so that a limited amount of adjustments of the length of the link 73 may be made. A cylinder 81 is carried in two depending portions 82 of the frame 37. The cylinder is pivoted on a cross rod 83 that is mounted on the depending portions 82 of the frame. Suitable connections (not shown) supply hydraulic fluid to the cylinder 81 to reciprocate the piston rod 75. There is, of course, a piston 84 within the cylinder 81 on the end of the rod 75.

The form of chuck closing device shown in Figures 5 and 6 comprises a guide frame made up of one U-shaped casting 85 and two end plates 86 and 87 that are bolted to the casting 85 at their side edges by bolts 88. The casting has a cylinder 89 secured to the bottom thereof by four rods 90 that extend through a head 91 of the cylinder and are threaded into the casting. The upper end of the cylinder is seated in a groove 92 in the bottom of the casting 85. A piston 93 in the cylinder has its piston rod 94 extending up through an aperture 95 in the bottom of the casting. A packing 96 is held in place by a cap 97 that is fastened by screws 98 to the casting.

Each of the end plates 86 and 87 has two guide ribs 99 and 100 formed thereon to direct two shoes 101 and 102 that are carried by a cross head 103 on the upper end of the piston rod 94. Wear plates 104 and 105 are fastened to the inner jaws of the end plates 86 and 87 for the faces of the shoes 101 and 102 to ride upon.

The cross head supports two shafts 106 and 107 each of which has two cam rollers 108 journaled thereon on opposite sides of the cross head. These cam rollers engage opposite chuck jaws 109 and 110. The chuck jaws are pivoted upon two stub shafts 111 and 112 that are mounted in the opposite walls of the casting 85. The jaw 109 has its bearings on the inner ends of the shafts, while the jaw 110 has its bearings between the first named bearings and the side walls of the casting.

The full and dotted line positions of the jaws 109 and 110 as illustrated in Figure 5 show how the jaws open by riding down on the rollers 108 as the cross head is lowered. The guides 99 and 100 and the plates 104 and 105 insure accurate guiding of the cross head in its vertical movement.

The final clamping action of the jaws is obtained by providing tapered side faces 113 and 114 on the jaws 109 and 110. These faces are provided by mounting tapered wear plates 115 and 116 on the chucks. These plates may well be of hardened steel and tapered to suit the particular work. A taper of about 5 degrees from the vertical is adequate in most cases. The operation of the wear plates is to make the final closing of the chuck jaws very slow and very powerful as the cross head moves upward at the final part of its stroke. All of the closing pressure is on the rollers 108 and not on the pivots of the jaws.

It is believed that the nature and advantages of my invention will be clear to those skilled in the art to which it is directed. It is evident that various minor modifications may be made without departing from the spirit and scope of the invention.

Having thus described my invention I claim:

1. Indexing and chucking mechanism for positioning and holding work pieces such as lengths

of tubing and rods, said mechanism comprising spaced apart guide members having upper edges along which the work pieces may be moved to position, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position.

2. Indexing and chucking mechanism for positioning and holding work pieces such as lengths of tubing and rods, said mechanism comprising spaced apart guide members having upper guide edges along which the work pieces may be moved to position, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position, the supporting means comprising opposed bell crank levers, an operating member and means connecting the member and the levers for moving the rollers in unison.

3. Indexing and chucking mechanism for positioning and holding work pieces such as lengths of tubing and rods, said mechanism comprising spaced apart guide members having upper guide edges along which the work pieces may be moved to position, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position, the supporting means comprising a slide carrying said rollers, and movable, to close the jaws, upwardly in a direction of a line through the pivotal axis of said jaws, and the center line of the jaws when closed, the cam faces on said jaws diverging toward the free ends of the jaws whereby said rollers wedge the jaws toward each other as they are raised.

4. Indexing and chucking mechanism for positioning and holding work pieces such as lengths of tubing and rods, said mechanism comprising spaced apart guide members having upper guide edges along which the work pieces may be moved to position, a work carrying reel for moving the work pieces into position, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position.

5. Indexing and chucking mechanism for posi-

tioning and holding work pieces such as lengths of tubing and rods, said mechanism comprising spaced apart guide members having upper guide edges along which the work pieces may be moved to position, work advancing means comprising a shaft above said members, spaced circular carriers fixed on said shaft and having notches in their peripheries for seating the work pieces, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position.

6. Indexing and chucking mechanism for positioning and holding work pieces such as lengths of tubing and rods, said mechanism comprising spaced apart guide members having upper guide edges along which the work pieces may be moved to position, work advancing means comprising a shaft above said members, spaced circular carriers fixed on said shaft and having notches in their peripheries for seating the work pieces, the upper guide edges on said guide members being substantially segments of a circle about an axis in substantially vertical alignment with said shaft, opposed chuck jaws pivoted to close upon a work piece positioned on said members, and to move below said guide edges for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position.

7. Indexing and chucking mechanism for positioning and holding work pieces such as lengths of tubing and rods, said mechanism comprising spaced apart guide members having upper concave supporting and guiding surfaces, along which the work pieces may be moved to position, a work carrying reel for moving the work pieces into position, opposed chuck jaws pivoted to close upon a work piece positioned on said members, and to move below said guide surfaces for passage of the work pieces to and from operating position, and means to close said chuck jaws comprising cam faces on the outer opposite surfaces of said jaws, rollers engaging said cam faces, and movable supporting means for said rollers operable to move the rollers upwardly to lift the jaws from open position into closed position.

8. Indexing and chucking mechanism for positioning and holding work pieces such as lengths of tubing and rods, said mechanism comprising spaced apart guide members having upper concave supporting and guiding surfaces, along which the work pieces may be moved to position, a work carrying reel for moving the work pieces into position, said guide members being adjustable vertically for positioning different sizes of work, opposed chuck jaws pivoted to close upon a work piece positioned on said members, and to move below said guide surfaces for passage of the work pieces to and from operating position, and means to close said chuck jaws comprising cam faces on the outer opposite surfaces of said jaws, rollers engaging said cam faces, and movable supporting means for said rollers operable to move the rollers

upwardly to lift the jaws from open position into closed position.

9. Mechanism for positioning and holding work pieces such as lengths of tubing and rods, comprising spaced supports, opposed chuck jaws for seizing a work piece on said supports, pivots for said jaws below the level of the supports, and means to close the jaws comprising bearing means on the outer opposite sides of said chuck jaws, spaced apart bearing members engaging said bearing means, and movable supporting means for said bearing members operable to raise and lower them in unison along lines of decreasing angularity with respect to the jaws as the jaws are brought to closed position, whereby to provide a powerful wedging action clamping the jaws to the work.

10. Mechanism for positioning and holding work pieces such as lengths of tubing and rods, comprising spaced supports, opposed chuck jaws for seizing a work piece on said supports, pivots for said jaws below the level of the supports, and means to close the jaws comprising bearing means on the outer opposite sides of said chuck jaws, spaced apart bearing members engaging said bearing means, and movable supporting means for said bearing members operable to raise and lower them in unison along lines of decreasing angularity with respect to the jaws as the jaws are brought to closed position, whereby to provide a powerful wedging action clamping the jaws to the work, said supporting means comprising two bell cranks pivoted on horizontal axes on opposite sides of the jaws, the bell cranks having means at one end engaging said bearing means, the other ends of said bell cranks being interconnected by two links and a lever, and a common drive member operatively secured to the lever and one of the links.

11. Mechanism for positioning and holding work pieces such as lengths of tubing and rods, comprising spaced supports, opposed chuck jaws for seizing a work piece on said supports, pivots for said jaws below the level of the supports, and means to close the jaws comprising bearing means on the outer opposite sides of said chuck jaws, spaced apart bearing members engaging said bearing means, and movable supporting means for said bearing members operable to raise and lower them in unison along lines of increasing angularity with respect to the jaws as the jaws are brought to closed position, whereby to provide a powerful wedging action clamping the jaws to the work, said supporting means comprising a vertically slidable drive member having opposed chuck jaw engaging members secured thereon.
- 12.
- 13.
- 14.
- 15.

12. Mechanism for positioning and holding work pieces such as lengths of tubing and rods,
- 20 comprising spaced supports, opposed chuck jaws for seizing a work piece on said supports, pivots for said jaws below the level of the supports, and means to close the jaws comprising bearing means on the outer opposite sides of said chuck jaws,
- 25 spaced apart bearing members engaging said bearing means, and movable supporting means for said bearing members operable to raise and lower them in unison along lines of increasing angularity with respect to the jaws as the jaws are
- 30 brought to closed position, whereby to provide a powerful wedging action clamping the jaws to the work, said supporting means comprising a vertically slidable drive member having opposed chuck jaw engaging members secured thereon,
- 35 and said bearing means comprising tapered plates on the chuck jaws.

BYRON F. BOWER,
